UNITED STATES PATENT OFFICE

2,509,134

HOLDER FOR PAPER CUPS

Herman Carew, Easton, Pa., assignor to Dixie Cup Company, Chicago, Ill., a corporation of Delaware.

Application October 29, 1945, Serial No. 625,343

2 Claims. (Cl. 65—61)

1

This invention relates to improvements in a holder for paper cups, and more particularly to a holder of the character highly desirable for use in drug, confectionery, and similar stores wherein individual soft drinks, sodas, and the like are dispensed, although the invention may have other uses and purposes as will be apparent to one skilled in the art.

It is desirable to use paper drinking cups, soda cups, and the like in holders in locations where sodas, soft drinks, and similar commodities are individually dispensed to the customers. The paper cups are destroyed after a single usage and are so economical as to warrant such practice and at the same time affect a material saving over the previous practice of utilizing glassware which had to be thoroughly cleansed after each usage and was subject to breakage.

Of course, it is desirable to insure the paper cup remaining in the holder until it is filled with the particular commodity, and until that commodity has been consumed by the customer. Means to maintain the cup in the holder must be provided without providing any movable parts upon the holder that must be operated in a certain way by the clerk or attendant. Likewise, the holder must be of such construction that it may be thoroughly cleansed, although cleansing of the holder need only be done at infrequent intervals and not after each serving of a soda or the like. In addition, the holder must be of economical construction and preferably of a substantially unbreakable character. In short, the holder should be of such character as to be capable of being dropped upon the floor without injury, and further of such character as to effectively grip a cup when the holder is merely pressed into position over a stack of inverted cups.

With the foregoing in mind, it is an object of the instant invention to provide a cup holder capable of automatically effecting a gripping action upon a paper cup by the mere axial disposition of the holder over the cup, and which holder may be very economically manufactured.

Another object of this invention is the provision of a paper cup holder equipped with means for automatically gripping a paper cup substantially entirely therearound.

It is also an object of this invention to provide a paper cup holder having a recess for the reception of a paper cup, with means defining a serrated edge projecting into the recess in position to automatically and grippingly engage the side wall of a cup.

2

Also a feature of this invention is the provision of a paper cup holder having a cavity for receiving a cup, with means projecting inwardly into that cavity to contact the cup wall, said means having a tortuous edge to insure a gripping action upon the cup.

It is also a feature of this invention to provide a holder for a conical paper cup, the holder having a generally conical recess therein for receiving the cup apex first, the recess having an open bottom through which the apical portion of the cup may extend, and there being an insert in the holder projecting into the recess near the apical portion with the insert provided with a tortuous inside edge to affect a gripping engagement with the wall of the cup.

Still another object of the instant invention is the provision of a plastic cup holder having a recess for the reception of a paper cup, and a metallic insert embedded in the wall of the holder, the insert being in the general form of a metallic ring with the inner edge of the ring having a saw-toothed configuration for gripping engagement with the cup wall.

Still a further feature of the instant invention resides in the provision of a plastic cup holder of generally hour-glass contour, and having a generally conical recess for the reception of a conical paper cup apex first, the recess being open at the bottom and the holder being provided with a metallic flat ring insert at the lower end of the recess, the insert having an inner annular saw-toothed edge for gripping engagement with the wall of the conical cup near the apex thereof so as to retain the cup in the holder against accidental dislodgment.

While some of the more salient features, characteristics and advantages of the instant invention have been above pointed out, others will become apparent from the following disclosures, taken in conjunction with the accompanying drawing, in which:

Figure 1 is a central vertical sectional view through a cup holder embodying principles of the instant invention, showing a soda cup in elevation positioned in the holder and grippingly engaged by the holder;

Figure 2 is a bottom plan view of the holder of Figure 1; and

Figure 3 is a greatly enlarged view of the right-hand portion of Figure 1 at the throat of the holder, showing the cup in section.

As shown on the drawings:

In the illustrated embodiment of this invention, there is shown a cup holder that is gener-

ally of hour-glass shape and which includes a body portion 1 and a base portion 2 preferably integral with the body portion. The holder is preferably molded out of a suitable thermosetting plastic, that plastic commonly known as Bakelite being one satisfactory plastic for this purpose.

The body portion 1 is provided with a generally conical cavity or recess 3 for the reception of a conical paper cup apex first. The cavity 3 is open at the bottom so the apical portion of the cup may extend through the opening into the hollow base portion of the holder.

In the illustrated instance, I have shown a conical paper cup 4 seated in the holder. This cup is of the type made from a single blank of stock convolutely wound into conical shape and provided with a rim bead 5 around the mouth. As seen clearly in Figure 1, the cup projects well without the holder at the top thereof so that the contents of the cup may be drunk by a consumer without danger of the consumer's lips touching the holder itself. There is also little danger of any of the commodity placed in the cup spilling over on the holder during filling of the cup, by virtue of the wide mouth of the cup. Thus, the holder need only be cleansed at infrequent intervals because it does not become soiled at every use, and yet there is no lack of sanitation insofar as the consumer is concerned.

In the present instance, in order to insure the cup remaining in the holder against accidental dislodgment, I have provided an insert in the holder, indicated by numeral 6. The insert is preferably disposed in the throat of the holder, and in the illustrated instance, the insert is at the bottom of the cup-receiving cavity 3. As seen best in Figure 2, the insert is in the form of a flat ring and is preferably made of metal. The inside edge of this ring is serrated or saw-toothed as indicated at 7 and this serrated edge projects inwardly sufficiently far to exert a gripping engagement upon the wall of the cup 4 in the apical region of the cup.

The insert 6 may be positioned so as to be molded in the holder at the time the holder is formed. Thus, the insert preferably becomes a permanent part of the holder. As seen in the drawing, one method of holding the insert in position is to mold a bead 9 in the hollow portion of the base of the holder below the insert so that a marginal portion of the insert is disposed above the bead or flange 9 while the upper face of the insert is seated against the inner wall of the hollow base around the open bottom of the cup-receiving cavity 3. Thus, the insert in effect forms a continuation of the cup-receiving cavity.

In use, the present invention is exceedingly simple, and yet quite positive in its action. Assuming that it is desired to position a cup in the holder and serve a soda or the like, the attendant merely grasps the inverted holder by the base, and seats it firmly on the uppermost one of a stack of inverted nested cups. Then the attendant, keeping its hold on the bottom of the holder, merely raises the holder and rights it, the cup being held in the holder by virtue of the insert 6 and carried along with the holder against accidental dislodgment by draughts or other causes. The cup is then filled with the desired commodity and served to the purchaser. The purchaser may drink from the cup, without any danger of the cup becoming accidentally dislodged and cascading down over the wearing apparel of the cus-

tomer. After the drink has been consumed, the holder and cup still firmly held by the holder may be returned by the attendant to a place where the cup may be pulled from the holder and dropped into a waste receptacle. Thus, if service is outside, there is no danger of the wind blowing the cups from the holder prior to filling or after the consuming of the drink. Likewise, there is no danger of the customer soiling his wearing apparel by the cup inadvertently falling out of the holder during use. It will be especially noted that at no time during the use of the holder and the serving of a drink does the attendant's hands come in contact with the cup itself. Further, it will be especially noted that there are no operating or movable parts for the attendant to waste time manipulating in order to firmly seat the cup in the holder. There is very little, if any, more effort on the part of the attendant to pick up the holder, and engage a cup therein, than there would be if the attendant picked up the customary and heretofore commonly used glass. From the greatly enlarged showing in Figure 3, it will be noted that when the cup is seated in the holder, the serrations or teeth 7 tend to bitingly or grippingly engage the wall of the cup, and each of these teeth will make a slight indentation in the wall of the cup as indicated at 10 in Figure 3. However, the teeth do not project inwardly sufficiently far to actually puncture the cup well, regardless of whether the teeth strike a double or single thickness portion of the wall. The biting engagement of the teeth illustrated in Figure 3 tends to effectively resist removal of the cup, and such engagement is sufficient to effectively prevent accidental dislodgment of the cup, although it is a simple expedient to grasp the mouth end of a used cup by the hand and pull it from the holder, or by inserting the thumb in the bottom of the holder to dislodge the cup by pressing against the apex thereof.

It will be understood, of course, that the holder need not of necessity be molded from plastic material, although that is a commercially satisfactory way of making the holder. Likewise, the insert 6 need not necessarily be of metal, but if it is of metal as preferred, it is of a non-rusting metal or a metal treated to resist rust.

It should also be noted that it is not essential that each and every one of the saw-teeth 7 actually bitingly or grippingly engage the cup wall. It is sufficient if a few of these teeth so engage the cup wall, but the provision of an annular series of such teeth insures a sufficient number of teeth engaging the cup wall to adequately hold the cup within the holder. It will also be noted that the teeth need not engage any edge portion of the cup such as an upper surface of a convolution, and that the teeth will equally as effectively engage a cup having no convolutions.

From the foregoing, it is apparent that I have provided a highly efficient, simple, and very economical form of cup holder capable of not only picking up a cup without any special manipulation of the holder or any part of it, but also capable of gripping that cup so as to sustain it within the holder against accidental dislodgment. It will be noted that the holder is very durable, substantially unbreakable in ordinary usage, and may be very thoroughly and easily cleansed whenever that becomes necessary.

It will, of course, be understood that various details of construction may be varied through a wide range without departing from the principles of this invention and it is, therefore, not the pur-

pose to limit the patent granted hereon otherwise than necessitated by the scope of the appended claims.

I claim as my invention:

1. A holder for a conical paper cup having a tubular portion of generally conical shape to receive therein a conical paper cup apex first, and a rigid fixed disc-like insert in said holder having a laterally saw-tooth edge projecting inwardly sufficiently to grippingly engage the cup wall and retain the cup in said tubular portion against accidental dislodgement.

2. A holder for a conical paper cup, said holder being made of a plastic material and of generally hour-glass shape, said holder having a generally conical recess for the reception of a conical paper cup apex first, said recess having an open bottom through which the apex of the cup extends, and a metallic centrally apertured disc-like insert in the throat of said holder having an edge portion projecting inwardly to engage the wall of a cup, said edge portion being laterally tortuous to enhance the gripping action of said insert on the cup upon a relative axial movement only between the cup and holder. 25
